UNITED STATES PATENT OFFICE.

ADAM CHOYNACKI, OF DETROIT, MICHIGAN.

BOTTLE-STOPPER.

1,031,322.

Specification of Letters Patent.

Patented July 2, 1912.

Application filed March 1, 1912. Serial No. 680,905.

To all whom it may concern:

Be it known that I, ADAM CHOYNACKI, a citizen of the United States, residing at Detroit, in the county of Wayne and State 5 of Michigan, have invented certain new and useful Improvements in Bottle-Stoppers, of which the following is a specification.

This invention relates to bottle stoppers and has for its object to provide an improved stopper of the cap type, in which the stopper is held in place by means of a locking hook which engages a loop at one side of the bottle neck, the cap being pivotally connected to a loop at the opposite 15 side of the bottle neck, so that when the hook is disengaged the cap may be swung open.

The invention is illustrated in the accompanying drawings in which—

Figures 1 and 2 are side elevations at a 20 right angle to each other of a bottle neck provided with the device. Fig. 3 is a top view. Fig. 4 is a section on the line 4—4 of Fig. 3.

Referring specifically to the drawings, 6 25 indicates a bottle neck. A band 7 of wire or the like is placed around this neck under the shoulder 8, and this band has at one side a loop 9 and at the other side a loop 10, the latter presented transversely, or so that the 30 hook may pass through the same. A metal cap 11 is connected to the loop 9 by means of a link 12, the link being hooked over a pin 13 which is held by folded knuckles 14 formed at one edge of the cap. A packing 35 or disk 15 is placed under the cap, and is held in position between tongues 18 at the outer edge of the cap. At the edge of the cap opposite to the hinge 14 is a depending projection or tongue 17 bent down to fit 40 beside the rim of the bottle. A pivot pin 18' is riveted to this tongue. A finger lever 19 swings on this pivot, from side to side, and this lever is provided with a hooked or curved finger 20 projecting from one side 45 thereof, in position to engage in the loop 10 and so hold the cap in closed position. The curvature of the finger is such that it has a

slight cam action, so that when the lever is pressed home it pulls down on the cap to force the stopper against the mouth of the 50 bottle.

To assist in locking the lever in position and prevent accidental loosening thereof, the tongue 17 is provided with notches or depressions 21, one of which is located above 55 the pivot 18' and the other of which is located below said pivot, and the upper end of the lever 19 is formed with bosses or projections 22 which when the lever is pushed down straight snap into said notches by 60 reason of the pressure of a spring 23 coiled around the pin 18' between the lever and a head 24 on the pin. The number of these notches and bosses may be increased if desired in order to increase the holding or 65 frictional contact between the parts.

To open the bottle it is held and the lever 19 is pressed laterally with sufficient force to retract the hook 20 from the loop 10, permitting the cap to be swung up or over 70 to the side of the bottle. The bottle can be resealed in an obvious manner, by the same stopper, and no tools are required either to close or open the stopper.

I claim:

In a bottle stopper, the combination of a 75 loop attached to the bottle neck, a cap hingedly attached at one side to the bottle neck and having a depending projection at the opposite side, a lever pivoted to said projection to swing transversely and having a spur adapted to engage in the loop, said projection and lever having engageable bosses and notches which are engaged when the lever is swung to locked position, and a 80 spring pressing the lever against said projection.

In testimony whereof, I affix my signature in presence of two witnesses.

ADAM CHOYNACKI.
